UNITED STATES PATENT OFFICE.

JOHN C. BENSON AND ANDREW C. BENSON, OF HUTTIG, ARKANSAS.

CHECK-VALVE.

1,147,292.

Specification of Letters Patent. Patented July 20, 1915.

Application filed June 13, 1914. Serial No. 844,905.

To all whom it may concern:

Be it known that we, JOHN C. BENSON and ANDREW C. BENSON, citizens of the United states, residing at Huttig, in the county of Union, State of Arkansas, have invented a new and useful Check-Valve, of which the following is a specification.

The present invention relates to improvements in check valves, one object of the invention, being the provision of a check valve provided with two oppositely operating connecting members, there being further provided means whereby one is held inoperative while the other is operative, thus selecting the direction in which the fluid passing therethrough is to be directed or checked.

A further object of the present invention, is the provision of a check valve of this character, by means of which the check valve selecting member may be readily adjusted without disturbing the parts and locked in such position by the means of an exteriorly disposed mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a side elevation of the complete valve. Fig. 2 is a section taken on line 2—2 of Fig. 1. Fig. 3 is a longitudinal sectional view through the complete valve.

Referring to the drawings, the numeral 1 designates the casing, which is provided with the web member 2 having the diverging portions 9 and 10, each of which is provided with a port so that the fluid may enter from one end of the casing and pass through the opposite end in either direction as desired. The web member 2 is provided with the transversely disposed rib 3 which is adapted to be abutted by the under side of the detachable or removable plug 4, which permits access to for repairing the parts of the valve.

The hinging elements 5 and 6 are provided for the respective valves or disks 7 and 8, the valve 7 being disposed to control the port in the portion 9 while the valve 8 is disposed to control the port in the portion 10, it being desirable that one of such valves

be held open and in such open position while the other valve is closed for automatic operation. Each valve is provided with the limiting resilient member 11 secured to the outer face thereof by means of the screw 12, and as particularly illustrated in Fig. 3.

To one side of the casing centrally thereof, is provided a hole or bore 13, the outer face of which is provided with the internally screw threaded socket 14, for the reception of the apertured plug 15. At the opposite side within the valve casing is provided a small socket 18 for the reception of the reduced end 17 of the valve selecting stem 16. This stem 16 is further provided with the squared portion 19 which fits in the squared opening or bore 20 of the valve selecting member 21. This member 21 is provided with the oppositely disposed ends 22 and 23 adapted to assume the full or dotted line positions as shown in Fig. 3, the end 23 being disposed to elevate and hold the valve 8 in its uppermost position to permit the flow of fluid from right to left as viewed in Fig. 3. Thus, the stem 16 is mounted for oscillation within the plug 15 and beyond the plug it is provided with the screw threaded portion for the reception of the locking disk 26, such disk 26 being provided with a handle 27 so that the same may be manipulated to release the stem relatively to the outer face of the plug 15 so that the same may be oscillated to adjust the selecting member for controlling either one of the valve members 7 or 8.

In order to manipulate the stem 16 and consequently the selecting member, the outer end of the stem 16 is reduced and squared as at 28 for the reception of the disk 29 and is provided with the operating handle 30. By this means when the locking disk 26 is released, the handle 30 may be operated to oscillate the stem 16 and consequently move the selecting member 21 to any desired position. When placed in such desired position, the locking disk 26 is then manipulated to lock the parts in such adjusted position. By means of the handles 27 and 30, the selecting member 21 may be adjusted exteriorly of the casing and thus indicate at a glance the relative position thereof as to the valve disks 7 and 8.

By this form of check valve as herein shown and described, the same may be readily attached to the pipes and the flap members 7 and 8 thereof be regulated so as

to permit of the passage of the fluid in either direction.

A coil spring 31 is seated within the socket 18 and exerts a pressure upon the stem 19.

5 What is claimed is:

1. A check valve, including a casing, two oppositely swinging flap members mounted therein, and a selective flap holding member mounted transversely of the casing and in 10 coöperative relation to the flaps.

2. A check valve, including a casing, said casing being provided with a centrally disposed web having two valve seats, two oppositely swinging valve disks mounted therein 15 for controlling the seat, and a selective means mounted transversely of the casing for engaging one valve at a time to regulate the same relatively to its seat.

3. A check valve, including a casing, said 20 casing being provided with a centrally disposed web having two valve seats, two oppositely swinging valve disks mounted therein for controlling the seat, a stem mounted

for oscillation transversely of the casing between the flap valves, means for oscillating the stem, means mounted on the stem and in the casing for engaging to elevate one flap valve at a time from its seat, and means for locking the stem in adjusted position. 25

4. A check valve, including a casing, two 30 oppositely disposed flap valves mounted therein, a stem mounted for oscillation transversely of the casing between the flap valves, a member having oppositely disposed arms carried thereby for engagement to elevate 35 one of the flap valves at a time, a locking disk for locking the stem in adjusted position, and means for manipulating the stem.

In testimony that we claim the foregoing as our own, we have hereto affixed our signatures in the presence of two witnesses.

JOHN C. BENSON.
ANDREW C. BENSON.
